CLOSURE FOR COLLAPSIBLE TUBES

George W. Parvis, Philadelphia, Pa.

Application March 26, 1938, Serial No. 198,163

7 Claims. (Cl. 221—60)

My invention relates to improvements in closures for collapsible tubes adapted for dispensing tooth pastes, shaving creams and the like.

The object of my invention is to provide a closure for tubes comprising a sliding tubular valve stem provided with a side opening, and adapted to be extended beyond the nozzle of the tube to expose said opening and said stem having novel means for discharging the material at an oblique angle relatively to the axis of the valve stem and away from the nozzle so that the material will not adhere to the latter.

A further object is to provide a closure for a tube comprising a nozzle in the form of a cap and a sliding valve stem having cooperating cutting edges formed by acute angles of the surfaces of the cap and the stem, arranged for insuring the abrupt and clean cutting off of the material when the stem enters the bore of the cap.

20 A further object is to provide cut-off means for limiting the flow of material, when the valve stem is in the open position.

A further object is to construct the closure with a concealed spring for closing the valve stem and provide stops for limiting the movement of the stem, which stops are constructed so that they will prevent the accumulation of the material between their adjacent surfaces, which would otherwise prevent the proper closing of the valve 30 stem.

A further object is to construct the closure parts so that they may be embodied in a cap and a nozzle of a tube as a unit structure, and also which may be embodied entirely within a 35 cap adapted to be removably attached to any standard tube.

These together with various other novel features of construction and arrangement of the parts, which will be more fully hereinafter described and claimed, constitute my invention.

Referring to the accompanying drawing:

Fig. 1 is an enlarged vertical section of a portion of a tube embodying my invention.

Fig. 2 is a view similar to Fig. 1 showing the 45 valve stem in the open position.

Fig. 3 is a horizontal section on line 3—3 of Fig. 1.

Fig. 4 is an inverted horizontal section on line 4—4 of Fig. 1.

50 Fig. 5 is an enlarged vertical section of a tube and a removable cap showing my invention embodied within the cap.

In the drawing in which like reference characters refer to like parts, 6 represents a collapsible tube having a discharge nipple 7 formed thereon. A cap 8 is mounted upon the nipple 7. In Figs. 1 and 2 the cap is shown permanently secured upon the nipple by any suitable means, such as a locking flange 9, formed upon the inner end 60 of the cap and secured to the nipple.

The outer end of the cap 8 is provided with an axial bore 10 positioned in alignment with the axis of the bore 11 formed through the nipple. A cylindrical valve stem 12 is slidably mounted in the bore 10 of the cap and has a sliding fit in the bore 11 of the nipple, which latter forms a bearing sleeve for the stem 12.

The stem 12 is provided with an annular collar 13, which is engaged by a spring 14, mounted within a recess 15 formed in the cap 8. The cap has a shoulder 16 which is engaged by the spring 14 which tends to move the stem until the collar 13 engages the nipple 7.

The stem 12 is hollow and is closed at its inner end by a plate 18 secured to the stem. Said stem is provided with inlet openings 20, formed through its cylindrical wall for the admission of material from the tube 6 to the axial passage formed through the stem.

The stem 12 is provided with a head 22 located at the outer end of the stem. The inner surface of the head forms a wall 23 which is inclined obliquely to the axis of the stem. The stem 12 has a discharge opening formed through the cylindrical wall adjacent to the head. The discharge opening 24 is defined by said inclined surface of the wall 23 and by the walls 25 and 26 of the stem. The inner surface, or wall 23, of the head is preferably in the form of a cone 28, having its apex extending inwardly toward the tube 6, and located upon the axis of the stem.

When the tube 6 is compressed the material will enter and fill the stem 12 and then force the stem outwardly against the action of the spring 14, until the discharge opening 24 is exposed beyond the cap 8. The inclined, or conical wall 23 will direct the material from the discharge opening 24 in the shape of a ribbon 29, which is extended in a line parallel with the surface of the wall 23, and away from the cap 8.

When the stem 12 is moved outwardly, to expose the opening 24 beyond the cap, the inlet openings 20 will be closed by the stem entering the nipple 7, as shown in Fig. 2, in which position the stem and the nipple form a cut-off for limiting the quantity of material which may be discharged each time the tube 6 is compressed.

The outer end surface of the head 22 is spherical and forms an acute angle with the inner surface of the wall 23, thus forming a peripheral knife edge 31, the diameter of which is coextensive in size with the diameter of the body portion of the stem. The outer end surface 32 of the cap 8 is spherical and forms an acute angle with the bore 10 of the cap, thus forming another knife edge 33. When the stem 12 is moved into the bore of the cap, to the position shown in Fig. 1, the knife edges 31 and 33 coact and cut the material clean, without any of the material adhering to the outside of the cap or the head.

The collar 13 is triangular in cross section and is beveled toward the nipple 7, forming a beveled surface 35 and reducing the size of the abutting surfaces between the collar 13 and the nipple 7, 5 so that in case any material works its way between the nipple and the stem 12 into the recess 15, it will be forced by the beveled surface 35 away from said abutting surfaces and allow the stem to fully enter the bore of the cap, as shown 10 in Fig. 1, and properly close the discharge opening 24.

Fig. 5 shows a form of my invention adapted to be embodied entirely within the cap and adapting the cap for use upon any tube having a nipple 15 of standard size. The cap 8a is provided with a screw-thread 38 for detachably mounting it upon a nipple 39 having a screw-thread 40. A bearing sleeve 42 is secured by pressing it into the cap. The stem 12a has a sliding fit within the bore 20 of the sleeve 42. Said stem is open at its inner end to receive material from the nipple 39 of the tube.

Various changes in the construction and arrangement of the parts may be made without 25 departing from my invention.

I claim:

1. A closure for collapsible tubes comprising a discharge member having an axial bore forming a discharge passage from the tube, a tubular valve 30 stem mounted within said bore for sliding movement, a wall closing the outer end of said stem, said stem having a side discharge opening located adjacent to said wall, said wall positioned at an oblique angle relatively to said bore and inclined 35 from the end of the stem adjacent to the tube toward said discharge opening and defining one wall of said opening for directing material through said opening obliquely relatively to said bore.

2. A closure for collapsible tubes comprising a discharge member having an axial bore forming a discharge passage from the tube, a cylindrical valve stem mounted within said bore for sliding movement, said stem having an axial passage 40 communicating with said tube at the inner end of the stem, said stem having a discharge opening formed through its cylindrical surface and located adjacent to the outer end of the stem, an inclined end wall upon the outer end of the stem 45 and defining an obliquely positioned discharge passage connecting said axial passage of the stem with said discharge opening, said obliquely positioned passage being inclined from the inner end of the stem toward the outer end thereof and arranged for directing material through said 55 opening obliquely relatively to said bore.

3. A closure for collapsible tubes comprising a discharge member having an axial bore forming a discharge passage from the tube, a tubular valve 60 stem mounted within said bore for sliding movement, a conical end wall closing the outer end of said stem, said conical wall having its apex presented inwardly toward said tube, and said stem having a peripheral discharge opening located 65 adjacent to the base of said conical wall.

4. A closure for collapsible tubes comprising a discharge nipple upon said tube, a cap mounted upon said nipple, said cap having an axial bore, a cylindrical tubular valve stem slidably mounted 70 within the bore of the cap, a head closing the outer end of said stem, said stem having a discharge opening formed through its cylindrical wall, said head having a conical inner surface,

a portion of said conical surface extending through said opening and converging with the outer end surface of said head and forming a peripheral knife edge coextensive in diameter with the diameter of the stem, and means tending to urge the stem into the bore of the cap to a position in which said head is within the bore of the cap. 5

5. A closure for collapsible tubes comprising a cap having an axial bore, a cylindrical tubular valve stem slidably mounted within said bore, a sleeve secured within the cap, said sleeve having an axial bore in which the inner end of the stem is slidably mounted, a collar upon the stem, a spring positioned between said collar and the outer end of the cap and arranged for moving the stem into a position to abut the collar against said sleeve, a head closing the outer end of the stem, said head having a conical wall positioned with its apex toward the interior of the stem, and said stem having a discharge opening formed through its cylindrical wall and located adjacent to said conical wall and arranged to be closed by the cap when the stem is moved by the spring to a position to abut the collar against said 20 sleeve. 25

6. A closure for collapsible tubes comprising a discharge member having an axial bore communicating with the tube, a cylindrical tubular valve stem mounted within said bore for sliding movement, a head closing the outer end of said stem, said stem having a discharge opening formed through the cylindrical wall thereof and located adjacent to said head, said stem having an inlet opening formed through the cylindrical 30 wall thereof and located adjacent to the inner end of the stem, a spring associated with said member and the stem tending to move the stem toward the tube to a position in which said inlet opening is exposed beyond the inner end of said bore for the entrance of material from the tube 35 into the stem and for closing said discharge opening within the bore, and a plate secured upon the inner end of the stem against which plate material under pressure within the tube will move the stem against the action of the spring to a 40 position to close said inlet opening within said bore and open said discharge opening beyond said bore. 45

7. A closure for collapsible tubes comprising a cap mounted upon said tube, a sleeve secured within the cap, said cap and sleeve having an axial bore, a valve stem slidably mounted within said bore, said stem having an axial passage, a head closing the outer end of said passage, a plate upon the stem and closing the inner end of said passage, said stem having an inlet opening formed through the side wall thereof and located adjacent to said plate, said stem having a discharge opening formed through the side wall thereof and located adjacent to said head, a collar upon the stem, a spring mounted within the cap and positioned between the outer end of the cap and said collar tending to move the stem into a position to open said inlet opening and close said discharge opening, and said openings located upon the stem relatively to the sleeve and the cap whereby said inlet opening will be closed by the sleeve and said discharge opening will be opened beyond the cap when the stem is moved against the action of the 50 spring. 55
